UNITED STATES PATENT OFFICE

109,888

DESIGN FOR A JACKET FOR A SHALLOW WELL PUMP

Robert G. Gracey, Oak Park, Ill., assignor to Crane Co., Chicago, Ill., a corporation of Illinois

Application April 4, 1938, Serial No. 76,269

Term of patent 14 years

To all whom it may concern:

Be it known that I, Robert G. Gracey, a citizen of the United States, residing at Oak Park, in the county of Cook and State of Illinois, whose post office address is 208 S. Maple Ave., Oak Park, Illinois, have invented a new, original, and ornamental Design for a Jacket for a Shallow Well Pump, of which the following is a specification, reference being had to the accompanying drawing, forming part thereof.

Fig. 1 is a front perspective view of a jacket
for a shallow well pump showing my new design.

Fig. 2 is a side perspective view thereof.

I claim:

The ornamental design for a jacket for a shallow well pump, substantially as shown.

ROBERT G. GRACEY.
